INSULATOR BRACKET

Clarence E. Dean, Birmingham, Ala., assignor to Dixie
Electrical Manufacturing Company

Filed Aug. 30, 1972, Ser. No. 285,011

Term of patent 14 years

Int. Cl. D13—03

U.S. Cl. D8—230

FIG. 1 is a front elevational view of an insulator bracket showing my new design;

FIG. 2 is a rear elevational view;

FIG. 3 is a plan view; and

FIG. 4 is a side elevational view.

I claim:

The ornamental design for an insulator bracket, substantially as shown.
